UNITED STATES PATENT OFFICE.

WILLIAM F. LAUTENSCHLAGER, OF CINCINNATI, OHIO, ASSIGNOR TO LORENZ MUTHER,
OF NEWTON, MASSACHUSETTS.

FOLDING MACHINE.

Application filed October 31, 1923. Serial No. 671,904.

The invention relates to machines for folding the edges of flexible material and more especially to a folding machine adapted for folding closed vamps and similar work.

5 In folding the edge of work in the form of an endless band, such, for instance, as a closed vamp in the shoe manufacturing industry, it is essential that the work should be so positioned in the machine as to avoid straining the edge which interferes with the attainment of perfect work. This is especially true of vamps having narrow throats. In consequence it has been found as a practical matter impossible to secure satisfactory 15 folding of closed vamps if the work is folded while in a flat condition. It has been customary heretofore to use a folding machine for this class of work having a narrow work-supporting arm over the end of which the closed vamp may be hung and folded, the main body of the vamp hanging downwardly in a free and unobstructed space under the arm. This method, however, has not been entirely satisfactory, especially for 25 narrow throated vamps.

In all the folding machines, however, heretofore in use, the work has been presented to the machine from the outside of the end of a single arm or the ends of a 30 double arm, if a double arm machine is used. I have discovered, however, that if the work is presented to the machine from the center thereof, so that the main body of the work lies under the over-hanging arm and is folded in this position, that all strain 35 upon the edge even in narrow throated vamps is obviated. The usual construction, however, of folding machines prohibits such a presentation of the work to the machine 40 since the various folding instrumentalities interfere with inserting the work from the center of the machine outwardly toward the folding instrumentalities on the end of the arm or arms of the machine.

45 One of the important features of my invention consists in providing a folding machine having a goosenecked lower arm, that is, an arm which is curved and having its work supporting end turned inwardly toward the main standard of the machine; an over-hanging arm being provided for

carrying the driven folding instrumentalities. This leaves a free and unobstructed space underneath the overhanging arm and between the work support and the main 55 standard of the machine in which the work may lie naturally when being folded.

Another feature of the invention consists in pivotally mounting the work support upon the end of the lower arm so that it 60 may be pivotally dropped when necessary to facilitate the insertion of work beneath the folding instrumentalities carried by the overhanging arm; said work support being so constructed that it is normally in an operative 65 position, irrespective of the pressure placed upon it, but may be depressed at the will of the operator by convenient means, such as treadle operated means. This construction permits the work to be 70 easily and expeditiously inserted in position from the center of the machine without effort or loss of time on the part of the operator.

Yet another feature of my invention 75 consists in making the lower arm of the machine detachable in order to permit lower arms of various constructions for doing different classes of work to be mounted in the machine. This is a feature of some importance 80 because it widens the range of the folding machine and permits the same machine with different arms to do all kinds of folding work.

In the drawings my invention is illustrated as applied to a folding machine employing the folding instrumentalities and the actuating mechanism shown and described in United States Letters Patent No. 1,399,264, issued to me on December 6, 1921, 85 in which Figure 1 is a side elevation of the operative end of the machine as viewed from the operator's seat; Fig. 2 is an end elevation of the same looking from left to right in Fig. 1; Fig. 3 is a bottom plan 90 view of the lower arm and work support; Fig. 4 is a plan view of the work support on an enlarged scale; Fig. 5 is a rear side elevation of the work support and supporting mechanism on an enlarged scale; Fig. 95 6 is a bottom plan view of the work support on an enlarged scale; Fig. 7 is a side ele-

vation on an enlarged scale of the operative support by means of a screw 50 and a washer 51 and having an obliquely curved periphery. The feed-bar 32 is at its lower end in the form of a foot 55 having teeth to grip the work and is provided with a 70 guide 56 secured thereto by a screw 57 having a guiding foot 58. The presser foot 34 for holding the work between the feeding movements is bent around to engage the work at a point adjacent to the feeding 75 members. The work is fed by what is termed a four-motion feed, that is, the feed-foot descends from its initial starting point to grip the work, then feeds forwardly, then lifts, releasing the work, and then returns 80 to its initial starting position, these movements being accomplished through the instrumentality of a feed-shaft 60 and a lift-shaft 61 mounted in suitable bearings in the standard and upper arm of the machine, the former imparting a forward and rearward 85 movement of the feed-bar and the latter an upward and downward movement of both the feed-bar and the presser-foot. On the forward end of the feed-shaft 60 is mounted 90 an extension 64 having one end in the form of a split collar 65 secured to the feed-shaft by a screw 66, the other end of the extension being in the form of a housing 67 within 95 which the feed-bar 32 reciprocates. The rocking of the feed-shaft 60 oscillates the housing 67 and imparts the forward and rearward movement of the feed-bar 32. Means for rocking the feed-bar and its mode of operation are fully shown and described in the said Letters Patent hereinbefore referred to, to which reference may 100 be made.

The up and down movement of the feed-bar and presser foot are accomplished 105 through the following means. Upon the end of the lift-shaft is secured a split collar 125 carrying a short arm 126 pivotally connected to a link 127, the upper end of which is forked to receive loosely a block 128 carried on a pin 129, forming a part of the split collar 130 fastened to the upper end 110 of the feed-bar 32 by a screw 131. A hood 133 serves as a buttress for a spring 135 set in the top of the feed-bar to hold the feed-bar in a lowermost position, a washer 136 being arranged between the collar 130 and the feed-bar housing 67.

The presser-foot 34 is pivoted at 140 on a rod journaled in a portion of the overhanging arm 12 and above the pivot point the presser-foot extends upwardly in the form of a flat finger-piece 143 permitting the presser-foot to be raised when desired. 115 A spring 145 set in an arm 146 forming a part of the arm 12 bears against the finger-piece 143 to hold it in a lowermost position, the pressure of the spring being regulated by a screw 147 bearing against one end of the spring and held in adjusted position by 120

The feeding mechanism comprises a feed-bar 32 and a co-operating feed-roll 33, the latter being loosely mounted in the work 125

a set nut 148. The presser-foot is raised by the lift-shaft at appropriate times through the instrumentality of a lug 150 secured on the collar 125 for engaging an adjustable screw 152 set in the presser-foot finger-piece 143, so that the presser-foot is raised by the rocking movement of the lift shaft.

The gage 30 and fold-turner or plow 31 are both of usual form and mounted on the work-support; the gage having an upright end 41 for guiding the material and the plow being carried by a flat piece 45 secured in position by a screw 46.

15 The fold-presser or hammer 35 which is novel in form, as will be described herein-after, is arranged on the lower end of a rod 160 mounted for reciprocation in a bearing 161 on the arm 12. A rock-shaft 165 in 20 bracket 166 and operated from the lift-shaft imparts the reciprocatory movement to the rod 160 through the following means. Upon a stud 180 is mounted a bell-crank lever 183 carrying threaded through the end of its 25 upper arm a bored screw 185 having a spring 184 adapted to engage the end of the hammer-rod 160. The other end of the bell-crank lever 183 is pivotally connected by a pin 186 to a yoke link 187 which in turn 30 is pivotally connected to the free end of an arm 188 by a pin 189; the other end of the arm 188 being in the form of a split collar 190 encircling the rock-shaft 165 and being fastened thereto by a screw 191. The 35 link 187 is made up of two yokes arranged at right angles to each other to act as a universal joint between the bell-crank lever 183 and the arm 188. The rocking of the rock-shaft 165 through the foregoing imparts a 40 downward motion to the hammer-rod 160 and hammer 35 to press the material as it is folded. To return the hammer-rod to a retracted position a spring 195 may be mounted on the rod, bearing at its lower end 45 against the portion 196 of the arm 12 and at its upper end against a split-collar 197 secured by a screw 198 upon the hammer-rod 160. (See Fig. 9.)

When curves of small radii are being 50 folded the work is pivoted at a point in front of the hammer and toward the operator in which case the pressing surface of the hammer 35 nearer to the operator should be advanced toward the operator in order 55 that the entire fold may be reached and pressed. For this reason I have found it of advantage to form the pressing surface of the hammer as shown in Fig. 8 with a projecting nose 300 so arranged that when the 60 hammer is turned toward the operator its pressing surface is extended in that direction and covers the entire folded edge on curves of small radii. The hammer is necessarily provided with a cutaway portion 302 65 which permits the nose of the hammer to be

turned into close proximity with the plow and thereby reach the folded edge on such curves as it leaves the plow and before the edge has had an opportunity to straighten up.

70 For turning the hammer whenever necessary and at the will of the operator, means may be provided capable of adjustment in order to determine the length of arc through which the hammer is turned in order to suit 75 various conditions of work. One form of such means is shown in detail in Figure 9, comprising a finger lever 306 fulcrumed on a pin 308 mounted in a yoke 310 secured by a screw 312 to a portion of the upper arm 80 12; the finger lever being provided with a lug 314 adapted to engage a cam block 316 formed on the split collar 197. A finger screw 320 which is threaded through the lower end of the finger lever 306 and held 85 in adjusted position by a set nut 322 may be used by the operator for depressing the finger piece to turn the hammer-rod and hammer. The finger screw 320 may also be used as a stop for limiting the movement of 90 the lever 306 in one direction and a stop 324 held in adjusted position by a set nut 326, may be employed for limiting it in the other direction. By adjusting these two stops 320 and 324 the length of the arc through which 95 the hammer is turned may be regulated to suit various conditions and various classes of work.

A slitting mechanism is shown of substantially the same construction and mode of operation described in the patent hereinbefore referred to in which 36 designates a knife-block secured in the work-support by a screw 212 and 37 a knife blade mounted on a knife-bar 213 and secured thereto by a 100 screw 216. The knife-bar is slidably mounted in a block or bearing 217 on the end of the arm 12 and is held against rotation by a guide-rod 219, also slidably mounted in said block 217 and secured by a screw 221 105 to a cross-bar 222 attached at its other end to the knife-bar 213. The knife-blade is reciprocated at the will of the operator from the rock-shaft 165 through the medium of a short arm 225 fastened on the end of 110 the rock-shaft 165 and pivotally connected by a pin 230 to another short arm 232 which in turn is pivotally connected to a link 234 pivotally connected to the cross-bar 222. At their junction point the arm 232 and link 115 234 are pivotally connected by an arm 235 to a depending bar 236 fastened at its lower end to a rod 238. A spring 245 fastened at one end to the lower end of the bar 236 and at its other end to the arm 12 holds the 120 said bar in normal position so that the junction point of the two arms, 232 and 235 and of the link 234 is normally on center with the rock-shaft 165. A stop screw 239 is threaded through the lower end of the arm 125 130

236 and bears against the arm 12 to permit adjusting the normal position of the arm 236 to secure an accurate centering.

As stated before, some of the important features of my invention reside in providing a lower arm which is goose necked in form and is detachable. In the drawings, 340 designates a lower arm constructed in accordance with my invention, which is arranged in the machine in a preferably horizontal position being curved rearwardly so as to leave a free and unobstructed space under the overhanging arm and in the center of the machine. This arm may be made 15 in skeleton form with supporting ribs 342 and is provided on its inner end with a plate 344 and a short shaft 346 adapted to fit in a suitable bore in the main standard 347 of the machine and to be secured there- 20 in in adjusted position by any suitable fastening means. The form of this arm is such that its outer end is turned inwardly toward the main standard of the machine and upon this end is pivotally mounted a work 25 supporting member comprising a rectangular frame 348 carrying a plate 350 secured thereto, upon which may be mounted the curved work supporting plate 25. The frame 348 is pivotally mounted upon a short 30 shaft 352 set in bearings 353 on the end of the arm 340. Any suitable means may be provided for supporting the frame 348 in normal operative position which will permit the frame to be moved pivotally down- 35 wardly to permit the work to be inserted and one such means is shown in the drawings comprising two links, 354 and 356; the upper of said links being pivotally connected by a screw pin 360 to a lug 362 40 formed on the under surface of the work supporting frame 348 and at its lower end to the link 356 by a screw-pin 364. The lower link is connected at its lower end by a screw-pin 366 to the end of a depending 45 bracket 368 formed on the end of the arm 340 and is provided with a lateral extension 370 so that it is substantially in the form of a bell-crank lever; the end of the extension being pivotally connected by a screw- 50 pin 372 to a rod 374 which may be connected at its lower end to a foot treadle not shown. The upper link is provided on its lower end with a foot 376 adapted to bear against the upper edge of the extension 370 on the lower link to prevent outward movement or breaking of the two links to the left as shown in Figure 5. These links are so arranged that the junction screw- 55 pin 364 is slightly beyond center with respect to the pins 360 and 366 when the links are in normal position so that pressure exerted upon the work-support will not cause the links to break. The depression of the foot-treadle and rod 374 causes the two 60 links to break and the work-supporting 65

frame to drop as shown by broken lines in Figure 5. To return the work-support to a normal operative position when the pressure on the foot treadle is released, a helical spring 380 may be mounted on the rod 374 70 abutting at its lower end a bracket 382 and at its upper end a collar 384 held in adjusted position by a set-screw 386. The spring is under sufficient compression to return the work-support to normal position automatically when the treadle is released. 75

In Figure 10 is shown an alternative form of arm 390 having its longitudinal axis in a vertical plane.

The operation of the machine so far as the folding instrumentalities are concerned is substantially the same as in the machine of the patent hereinbefore referred to with the exception of such improved results as may be secured by the modified form of fold- 80 pressing means herein shown. In folding work in the form of an endless bank such as a closed vamp, the work is presented to the machine from the inside; that is, from a point between the work-support and the main standard of the machine. In such case the operator depresses the foot-treadle thereby dropping the work-support, then places the work in position on the work- 85 support and releases the treadle whereupon the spring forces the work-support back to normal position and the machine may then be started on the folding operation. 90

In presenting the work in this manner, the main body of the work lies in the clear unobstructed space under the overhanging arm between the work-support and the main standard and assumes a natural position which does not strain the edges which have been and are being folded. I have found 100 that closed vamps can be folded to much better advantage and better results can be secured when the vamp is thus presented to the machine. I have also found that the work is fed through the machine with 105 greater ease and facility when thus presented. 110

Although the illustrated embodiment of my invention is designed with special reference to folding closed vamps, it is to be observed that it may also be employed for other kinds of work. In the general run of flat work, it may be used in the ordinary manner, the work being presented to the machine from the outside in the ordinary manner, in which case, it is unnecessary to drop the work-support. 115

It is to be understood that my invention is not to be limited to the specific construction herein shown and described nor to the particular folding machine shown since the foregoing is merely illustrative of the invention and its application and it is capable of embodiment in other forms of construction and of application to folding machines 120 125 130

of other constructions all within the pur-
view of the following claims.

What I claim is:—

1. A folding machine having in combina-
tion a frame provided with an overhanging
arm and a lower arm, said lower arm being
curved longitudinally to leave a free and
unobstructed space under the main portion
of said overhanging arm to permit work to
be inserted from the center of the machine
and to be moved freely in said space, a work
support pivotally mounted on the end of
said lower arm facing inwardly and adapted
to be dropped to permit said work to be in-
serted, fold turning means carried by said
work support and feeding and fold pressing
means carried by said overhanging arm. 70
2. A folding machine having in combina-
tion a frame provided with a projecting arm
curved longitudinally to leave a free and un-
obstructed space between its end and the
frame of the machine for the insertion and
handling of work, a work support pivotally
mounted on the end of said arm facing in-
wardly and adapted to be dropped to facili-
tate the introduction of said work, fold turn-
ing means carried by said work support, an
overhanging arm having its end adjacent to
the end of said projecting arm and feeding
and fold pressing means carried by said
overhanging arm. 80
3. A folding machine having in combina-
tion a frame provided with a lower arm and
an upper overhanging arm, said lower arm
being curved longitudinally to leave a free
space under the main portion of said over-
hanging arm for the insertion of work from
the center of the machine, a work support
pivotally mounted on the end of said lower
arm and extending inwardly and normally
in operative position and means within the
control of the operator for pivotally moving
said work support to permit the insertion
of work from the center of the machine. 90
4. A folding machine having in combina-
tion an upper overhanging arm, a lower arm
having its longitudinal axis approximately
in the form of a semi-circle to leave a clear-
ance space under said upper arm, the ends
of the two arms being in juxtaposition, a
work-plate pivotally mounted on the end of
said lower arm and extending inwardly to-
ward the center of the machine, and means
for depressing said work-plate pivotally to
permit work to be inserted from said center. 100
5. A folding machine having in combina-
tion an upper overhanging arm and a lower
curved arm, the longitudinal axis of said
lower arm being in the form of a semi-cir-
cle, in order to leave a clear and unob-
structed space in the center of the machine
and under said overhanging arm, the ends
of said two arms being arranged in juxtapo-
sition, a work-support pivotally mounted
on the end of said lower arm and extending
inwardly toward the center of the machine. 110
6. In a folding machine, the combination
of an overhanging arm, feed and fold press-
ing means carried by said arm leaving a free
and unobstructed space under said overhang-
ing arm, a goose-neck lower arm, a work
support pivotally mounted on said lower
arm and extending inwardly, folding means
carried by said work support and treadle
operated means for lowering said work sup-
port to permit work to be inserted and re-
moved from the center of the machine and
automatic means for returning said pivotally
mounted work support to normal position
when the pressure upon said treadle
operated means is relieved. 120
7. A folding machine having in combina-
tion, a goose-neck arm, a work support piv-
otally mounted on said arm, an overhang-
ing arm, feeding and fold pressing means
carried by said overhanging arm, fold turn-
ing means mounted upon said work support
and means within the control of the opera-
tor for moving said work support pivotally
away from said feeding and fold pressing
means in order to permit work to be in-
serted therebetween. 130
8. A folding machine having, in combina-
tion, a frame including a lower arm and an
upper arm, the ends of said two arms be-
ing adjacent and said lower arm being
curved outwardly from the central axis of
said frame in order to permit work to be
placed within the curve of said lower arm
and underneath said overhanging arm, a work
support carried by said lower arm, folding
means mounted upon said work sup-
port and feeding and fold turning means
mounted upon said upper arm. 140
9. A folding machine having, in combina-
tion, a frame including a lower horizontal
arm and an upper arm, the ends of said
two arms being adjacent and said lower
arm being curved outwardly from the cen-
tral axis of said frame in order to permit
work to be placed within the curve of said
lower arm and underneath said overhanging
arm, and a work support pivotally mounted
on the end of said lower arm and extending
inwardly toward the center of the machine. 150
10. A folding machine having, in combina-
tion, a frame including a lower arm and
an upper arm, the ends of said two arms be-
ing adjacent and said lower arm being
curved outwardly from the central axis of
said frame in order to permit work to be
placed within the curve of said lower arm
and underneath said overhanging arm, feed-
ing and fold pressing means carried by said
upper arm, a work support pivotally mount- 160

ed on the lower end of said arm and extending inwardly toward the center of the machine, and means within the control of the operator for moving said work support pivotally away from the feeding and fold pressing means in order to permit work to be inserted therebetween.

11. A folding machine having, in combination, a main frame, provided with an upper overhanging arm and a lower goose-neck arm, the ends of said arms being in close proximity to each other, and a work-support pivotally mounted on the end of said lower arm and extending inwardly toward the center of the machine.

12. A folding machine having, in combination, a main frame, provided with an upper overhanging arm and a lower goose-neck arm, said lower arm being detachable from said frame, and a work-support pivotally mounted on the end of said lower arm and extending inwardly toward the center of the machine.

13. A folding machine having, in combination, a main frame provided with an upper overhanging arm and a lower goose-neck arm, said lower arm being adjustably and detachably mounted in said frame and a work-support carried by said lower arm and extending inwardly toward the center of the machine.

14. A folding machine having, in combination, a frame provided with an overhanging arm and a lower goose-neck arm, a work-support pivotally mounted on the end of said lower arm and extending inwardly toward the center of the machine, a pair of links for supporting said work-support in a normal operative position and means for breaking said links at their junction point

at the will of the operator to depress said work-support.

15. A folding machine having in combination a main frame comprising a standard, an upper overhanging arm and a lower arm having its main longitudinal axis curved and its end turned reversely toward the said standard of the frame, a work-support pivotally mounted on the end of said lower arm and extending toward said standard, folding instrumentalities mounted on said work-support and on the lower end of said overhanging arm for co-operative action, a pair of links for supporting said work-support in normal operative position and treadle-operated means for breaking said links at their junction point at the will of the operator to depress said work-support and allow work to be mounted thereon.

16. A folding machine having, in combination, a frame provided with an upper overhanging arm and a lower arm curved longitudinally to leave a free and unobstructed space between its end and the frame of the machine for the insertion and handling of work, a work support pivotally mounted on the end of said lower arm and extending inwardly toward the center of the machine, a pair of links for supporting the free end of the said work support in operative position, treadle operated means for breaking said links at their junction point to drop pivotally said work support to permit the insertion of the work and a spring for returning said work support to normal position whenever the pressure on said treadle is released.

In witness whereof, I hereunto set my hand this eleventh day of October, 1923.

WILLIAM F. LAUTENSCHLAGER.
